CIRCUIT BREAKER CASE

Charles Mune, Trenton, N.J., assignor to Heinemann
Electric Company, Trenton, N.J.

Original design application Aug. 2, 1971, Ser. No.
168,534, now Patent No. 230,275. Divided and
this application Feb. 4, 1974, Ser. No. 439,588

Term of patent 14 years

Int. Cl. D13—03

U.S. Cl. D26—13 R

Fig. 1

Fig. 3

Fig. 2

FIG. 1 is a front, side and bottom perspective view of a circuit breaker case showing my new design;

FIG. 2 is a back and top perspective view thereof, but showing the other side, and omitting the terminal shown in FIG. 1 in dot-dash lines; and

FIG. 3 is a top plan view thereof, but omitting the terminal shown in FIG. 1 in dot-dash lines.

The broken lines are for illustrative purposes only.

This is a divisional application based on design application Ser. No. D. 168,534, filed Aug. 2, 1971 now Pat. D. 230,275, Feb. 5, 1974.

I claim:

The ornamental design for a circuit breaker case, as shown and described.
